UNITED STATES PATENT OFFICE.

MAX FISCHMANN, OF TORONTO, ONTARIO, CANADA.

CUSHION.

1,192,510.

Specification of Letters Patent. Patented July 25, 1916.

Application filed February 15, 1915. Serial No. 8,254.

To all whom it may concern:

Be it known that I, MAX FISCHMANN, of the city of Toronto, in the county of York, in the Province of Ontario, in the Dominion of Canada, have invented certain new and useful Improvements in Cushions; and I hereby declare that the following is a full, clear, and exact description of the same.

This invention relates to cushions of the type in which springs are used as a resilient foundation and is particularly applicable for use with automobiles, ambulances and the like, having for its object to provide means whereby the abnormal shock due to sudden compression of the cushion will be absorbed, thereby preventing the total collapse of the cushion and the consequent shock to a person who may be seated thereon.

Further objects are to provide for the elimination of noise or contact of the said springs one with another and to effect, if desired, the partial compression of certain of said springs in order to increase their efficient operation.

The invention consists essentially of the novel construction and arrangement of the parts whereby the primary springs forming the foundation of the cushion are reinforced, either directly or indirectly, by further resilient members which may be of greater strength than the primary springs. Pockets are preferably provided for the accommodation of the said springs and their reinforcing means, the springs if desirable being in a state of partial compression within the said pockets and a suitable fibrous material extending around the said pockets both between the same and between the outer covering of the cushion, all of which is more particularly described in the following specification and with reference to the accompanying drawing in which,—

Figure 1 is a sectional perspective view of part of a cushion made according to this invention, certain parts being broken away to more clearly illustrate the structure. Fig. 2 is a sectional detail view illustrating the primary spring within one of the pockets and a secondary spring concentrically disposed within said primary spring and also provided with a pocket. Fig. 3 is a transverse section of Fig. 2. Fig. 4 illustrates a method in which the primary spring may be reinforced and the separate secondary spring

dispensed with. Fig. 5 illustrates as an example another arrangement of the springs, and Fig. 6 is a plan of the same.

Similar characters of reference indicate similar parts in the several figures of the drawing.

1, 1, are the main or primary springs forming the foundation of the cushion and arranged perpendicularly therein, the said springs being attached directly to the frame of the cushion, where such a frame is employed, but it is preferred to dispense with such frame and arrange the springs in fabric pockets 2, the said fabric pockets being surrounded by felt or other suitable fibrous material 3 in such a manner that the internal construction of the cushion will be in the form of a series of spring containing rolls A. A. extending from side to side, the said series of rolls preferably being further covered with a layer of fibrous material 4 between the same and the outer covering or envelop 5.

Where cushions are so provided with main or primary springs only, especially where used in connection with automobiles, it is found that they work very satisfactorily under ordinary conditions, but upon the vehicle passing over a very uneven surface the violent shock will effect the total collapse of the cushion, beneath the weight of the person seated thereon, the shock therefore being directly transmitted to the person with consequent discomfort.

In the present case the total collapse of the cushion under such circumstances is prevented by the resilient reinforcement of the said springs 1 for a part of their length in such manner that after the primary springs 1 have been compressed to a certain extent the reinforcement will come into operation, thereby increasing the proportion of force necessary for the further compression of the cushion. The most convenient form of such resilient reinforcement are secondary springs 6 substantially shorter than the primary springs, although, for example, pads of porous rubber or the like may be used for a similar purpose if desired. These springs 6 may be concentrically arranged within the springs 2, or may be integral therewith as indicated in Fig. 4 whereby the primary springs 2 are practically self reinforced.

7 are fabric pockets surrounding the reinforcing springs 6 and preventing noise, which may be caused by contact between the primary and secondary springs, while also having as one of their objects to retain the said secondary springs in a state of partial compression, if so desired, in order to increase their efficient operation.

12 The proportionate number of primary and secondary springs may be varied according to requirements as may also the respective positions of the said primary and secondary springs, Fig. 5 of the drawing indicating, as an example, an alternative arrangement.

15 With a cushion of this description the required resiliency may be obtained for comfort under ordinary circumstances, while providing for increased resistance in the cushion when subjected to abnormal shock,

22 thereby particularly adapting it for use in connection with automobiles or ambulances.

25 This invention may be developed within the scope of the following claims without departing from the essential features there-

of, and it is desired that the specification and drawing be read as being merely illustrative

and not in a limiting sense, except as necessitated by the prior art.

What I claim as my invention is:

1. In combination with a cushion, having 30 primary springs forming the foundation of said cushion, and secondary springs, substantially shorter than said primary springs, and upon common axes with said primary springs, individual pockets also substantially shorter than said primary springs adapted to retain said secondary springs coaxially within said primary springs.

2. In combination with a cushion having 40 primary springs forming the foundation of said cushion, and secondary springs, substantially shorter than said primary springs, pockets in which said secondary springs are inclosed and maintained in a state of partial compression.

Signed at Toronto, in the county of York, in the Province of Ontario, in the Dominion of Canada, this 14th day of January, 1914.

MAX FISCHMANN.
